UNITED STATES PATENT OFFICE

CLIFFORD L. SNYDER, OF DETROIT, MICHIGAN, ASSIGNOR TO EVANS PRODUCTS COMPANY, OF DETROIT, MICHIGAN, A CORPORATION OF DELAWARE

CHOCK BLOCK

Application filed May 27, 1931. Serial No. 540,435.

This invention relates to certain new and useful improvements in chock blocks.

The primary object of the invention is to provide a chock block comprising a casting or metal stamping of substantially inverted V-formation providing angularly disposed walls with one wall fashioned for intimate contact with a vehicle wheel tire while the other wall constituting a brace arm is designed to resist excessive strains under impact.

A further object of the invention is to provide a metal chock block of the foregoing character wherein the rear wall thereof is transversely curved to increase the strength thereof and practically eliminate collapse of the arched wall in the presence of severe stresses under impact.

It is a further object of the invention to provide a transversely curved brace wall in a metal chock block that is corrugated in a lengthwise direction for increasing the strength of the brace wall and chock block.

With the above and other objects in view that will become apparent as the nature of the invention is better understood the same consists in the novel form, combination and arrangement of parts hereinafter more fully described, shown in the accompanying drawings and claimed.

In the drawings:

Figure 1 is a perspective view of a metal chock block constructed in accordance with the present invention, showing the dished wall for the support of a vehicle tire and transversely arched angularly disposed brace wall;

Figure 2 is a side elevational view;

Figure 3 is a vertical longitudinal sectional view taken on line 3—3 of Figure 1;

Figure 4 is a horizontal sectional view taken on line 4—4 of Figure 2 showing the transversely arched corrugated rear brace wall of the chock block;

Figure 5 is a horizontal sectional view,

similar to Figure 4, showing the rear brace wall transversely curved and uncorrugated;

Figure 6 is a perspective view of another form of chock block wherein the corrugations or reinforcing ribs are formed in both walls of the block; and

Figure 7 is a fragmentary side elevational view showing a bent over reinforcing anchor toe for the block.

In metal chock blocks of the general character disclosed herein, it has heretofore been

customary to form the walls thereof in straight lines, of a flat characteristic with the result that the brace wall section thereof that is subjected to severe stresses in service is subject to collapse and for this reason, a sheet metal or stamped chock has been impractical.

The gist of this invention resides in the strengthening of the brace wall of the chock and is accomplished by transversely curving the brace wall and in actual practice, this particular design of brace wall has proved highly efficient and able to withstand severe stresses in service and it has also been found that by the provision of longitudinally extending corrugations in the transverse curved brace wall, additional strength is added thereto so that a metal chock block while comparatively light in weight can be possessed of sufficient inherent strength for the proper bracing and supporting of a motor vehicle during shipment.

Referring more in detail to the accompanying drawings, the chock block illustrated in Figures 1 to 4 is formed of metal and preferably stamped from a blank into substantially inverted V-formation, comprising a front wall 10 and a rear wall 11 with the median line 12 forming the upper end or head of the chock. The wall 10 of the chock is provided with a relatively deep depression 13 extending substantially the entire length thereof and spaced from the side edges of the support of a vehicle wheel tire and said wall 10 at opposite sides of the depression 13 extend

in straight lines from the lower to the upper ends of the wall with a longitudinally extending depression 14 parallel with each edge defining a reinforcing bead, the beads extending substantially the full length of the side edges of the wall 10. The lower edge of the wall 10 carries an anchor toe 15 extending outwardly thereof with corner openings 16 therein for the passage of anchor devices, such as nails or spikes.

10 The other wall 11 of the chock which constitutes the brace wall is transversely curved as at 11a over the entire length thereof and said transverse curvature extends through the upper end 12 of the chock. By the provision 15 of the transverse curvature in the wall 11, the bracing characteristic of said wall is greatly increased over the usual straight or flat wall so that collapse of the brace wall 11 is practically eliminated, it being understood that 20 this wall of the chock block is subjected to severe stresses and strains when the chock is in service. With the idea of further increasing the bracing strength of the wall 11, the same is longitudinally corrugated as at 17, 25 substantially over the entire length thereof. The lower end of the wall 11 carries an anchor heel 18 directed outwardly thereof at an angle and provided with openings 19 for the passage of hold fast devices such as nails, 30 spikes etc.

In the form of the invention shown in Figure 5, the wall 10a of the chock has the wheel tire supporting depression 13a formed 35 therein and the side edges of the wall 10a laterally of the depression 13a are rolled as at 14a for reinforcing purposes. The other wall 11b is transversely curved for increasing the bracing strength thereof, but is unprovided with corrugations as illustrated in Figure 4.

40 Another form of the invention is shown in Figure 6, the chock block being of inverted V-formation having walls 20 and 21, the wall 20 having a tire receiving depression 22 therein, the wall 21 being transversely curved as at 21a while reinforcing beads 22 are formed in both walls 20 and 21 and extend over the upper edge of the chock.

45 It is also intended to reinforce the anchor toe for the chock as illustrated in Figure 7, the toe 15a being bent upon itself as illustrated.

The gist of this invention resides in the 50 provision of the transversely curved wall of the chock and increased resistance to the bending of a curved wall over a flat wall is a known fact as set forth in Mark's Mechanical Engineers Pocket Book, 1924. The publication 55 shows a relative resistance between straight and curved plates as being approximately of the ratio of 1 to 376. The increased strength 60 of a curved wall in the present instance will at once be appreciated when compared with 65 a flat wall heretofore employed in this art

and by the use of such a curved wall, the metal chock block may be of comparatively light weight and still accomplish its purpose.

While there are herein shown and described the preferred embodiments of the invention, it is nevertheless to be understood 70 that minor changes may be made therein without departing from the spirit and scope of the invention as claimed.

I claim:

1. A one-piece metallic chock of inverted 75 V-shape comprising a pair of angularly disposed walls, one for the support of a wheel tire, the other wall constituting a brace and being transversely curved over the length thereof, and said curved wall being longitudinally corrugated.

2. A one-piece metallic chock of inverted 80 V-shape comprising a pair of angularly disposed walls, one for the support of a wheel tire, the other wall constituting a brace and being transversely curved over the length 85 thereof, and both of said walls being longitudinally corrugated.

3. A one-piece metallic chock of inverted 90 V-shape comprising a pair of angularly disposed walls, one for the support of a wheel tire, the other wall constituting a brace and being transversely curved over the length 95 thereof, the walls of said chock being longitudinally corrugated from end to end, with the corrugations extending over the upper edge of the chock.

4. A one-piece metallic chock formed of stamped metal and of inverted V-form providing angularly disposed walls, one wall having a depression therein inwardly of its border for the support of a wheel tire with the side edges of the wall adjacent the depression extending in straight lines from the toe to the head and the other wall being transversely curved throughout the length thereof with the curvature extending into the head of the tire supporting wall.

In testimony whereof I affix my signature.

CLIFFORD L. SNYDER.
